LOCOMOTIVE CONTROL SYSTEM

Application filed March 7, 1931. Serial No. 520,993.

My invention relates generally to control systems, and more particularly, to control systems for Diesel-electric locomotives.

An object of my invention, generally stated, 6 is to provide a control system which shall be simple and efficient in operation and which may be economically manufactured and installed.

A more specific object of my invention is to 10 provide for automatically stopping a Diesel-electric locomotive in case the operator becomes disabled.

Another object of my invention is to provide 15 for controlling a Diesel-electric locomotive from a plurality of stations.

Other objects of my invention will be described fully hereinafter or will be apparent to those skilled in the art.

For a fuller understanding of the nature 20 and scope of my invention, reference may be had to the following detailed description, taken in conjunction with the accompanying drawing, in which:

The single figure is a diagrammatic view of 25 a control system constructed in accordance with my invention.

Referring to the drawing, a motor 10, which 30 may be of any suitable type, is utilized for propelling a vehicle (not shown). In the particular embodiment of the invention illustrated, a series motor, having an armature winding 11 and a series field winding 12, is provided.

The power for operating the motor 10 is 35 supplied by a generator 13, of the shunt-wound type, having an armature winding 14 and a shunt field winding 15. An electrically-operated switch 16 is provided for connecting the generator 13 to the motor 10.

An internal-combustion engine 17, which 40 may be of the well known Diesel type, is provided for driving the generator 13 to supply power for operating the vehicle. In this manner, a self-propelled locomotive is provided which does not require electric power 45 from an external source to operate the vehicle, and, therefore, does not require a trolley conductor for conducting electric current to the propelling motor, as is the case with electric locomotives of the usual type.

A locomotive of the Diesel-electric type is particularly suitable for use as a switching locomotive, in that no complicated overhead trolley system is required to supply it with power.

The supply of fuel to the engine 17 is controlled by a throttle 18, which may be actuated by an electro-pneumatic mechanism 19. The throttle 18 is actuated by a piston 21, which is disposed in an air cylinder 22. 60 The operation of the piston 21 may be controlled by a magnet valve 23, which is of a standard type, well known in the art. The magnet valve 23 regulates the flow of compressed air from an air reservoir 24 to the air cylinder 22. The throttle 18 may be so adjusted that the engine will operate at an idling speed when the air is permitted to be exhausted from the cylinder 22 through the magnet valve 23, thereby permitting a spring 70 25 to actuate the piston 21 to the closed or lower position, as viewed in the drawing. When the actuating coil of the magnet valve 23 is energized, air is admitted to the cylinder 22 through the magnet valve 23 from the air reservoir 24, thereby compressing the spring 75 25 to open the throttle 18.

As is the usual practice, an air-brake system is provided on the locomotive for controlling its speed and for stopping it when 80 necessary. Since the brake system may be of any standard type, well known in the art, it has been deemed unnecessary to give a detailed description of its structural and operating features in this specification. The operation of the air brakes may be controlled by a brake-applicator valve 26 which is of a standard type. The valve 26 controls the admission of air to the conductor 27, which 85 leads to the brake-operating mechanism (not shown). The operation of the valve 26 is controlled by a magnet valve 28 which is similar to the magnet valve 23.

As is well known in the art, the brake applicator valve 26 may be so constructed that 90 the brakes will be released from the wheels of the locomotive when the air pressure is balanced on the two sides of the valve 26. When the coil of the magnet valve 28 is energized, 95 air is admitted to one side of the valve 26, 100

through a conductor 29, to balance the air pressure applied to the other side of the valve 26 through a conductor 31, thereby releasing the air brakes. When the magnet valve 28 is deenergized, the air is permitted to be exhausted from the one side of the valve 26 through the conductor 29, thereby causing the brakes to be applied to the wheels of the locomotive.

10 The operation of the above-described equipment may be controlled by a master controller 32 which may be of the drum type, having a plurality of contact fingers disposed to engage the contact segment 33. As illustrated, the drum of the controller 32 is disposed to be actuated by a pulley 34.

15 In order that the operation of the locomotive may be controlled from either side of the locomotive cab, or from a plurality of stations within the cab auxiliary controllers 35 and 36 are provided. The auxiliary controller 35 may be located on one side of the locomotive cab, while the auxiliary controller 36 may be on the other side. As shown, 20 the master controller 32 may be actuated, through either of the auxiliary controllers, by means of cables 37 and 38 which connect the pulleys, provided on the auxiliary controllers 35 and 36, to the pulley 34 on the master controller 32.

25 In order that the locomotive shall be automatically stopped in case the operator becomes disabled, the auxiliary controllers 35 and 36 are provided with contact segments 31 and 42, respectively, which are disposed to be actuated by handles 43 and 44, commonly known as "dead man's handles".

30 The contact segments 41 and 42 of the auxiliary controllers are disposed to be engaged 40 by a plurality of contact fingers, and are actuated to the "out" position by springs 45 and 46, when the handles 43 and 44 are released. The auxiliary controllers 35 and 36 are so interconnected that the operation of the locomotive may be controlled by either of the controllers. They are also connected in such 45 manner that the locomotive will be automatically stopped when both of the handles 43 and 44 are permitted by the operator to remain in the released position, as shown in the drawing, for a predetermined time interval.

50 In order that the stopping of the vehicle shall be delayed for a short time, after the controller handle is released by the operator, or, in case the operator has not become disabled but is merely passing from one side of the locomotive to the other, a time-delay relay 47 is provided which functions to delay the stopping of the locomotive for a predetermined time interval. This is of the same 55 general construction and operates in the same manner as the relay disclosed in the patent to W. G. Cook, No. 1,753,983, granted on April 8, 1930.

60 Briefly described, the relay 47 is of the elec-

tro-magnetic type, having an armature 48 pivotally mounted upon a core 49. The relay is provided with two coils 51 and 52, which are so wound as to oppose each other magnetically. When the coil 51 is energized, a 70 magnetic flux is established in the core 49 which actuates the armature 48 to the closed position. The flux established by the coil 51 is opposed by the coil 52 which is constantly energized. When the armature 48 is closed, 75 a closed magnetic circuit is established through the armature 48 and the core 49. Therefore, when the coil 51 is deenergized, the time rate of decay of flux in the magnetic circuit may be controlled by varying the current in the deenergizing coil 52. In this manner, the time at which the spring 53 will cause the armature 48 to open, after the coil 51 is deenergized, may be varied within pre-determined limits. The time setting of the 80 relay 47 may also be varied by adjusting the tension of the spring 53. The amount of current in the coils 51 and 52 may be controlled by resistors 54 and 55.

85 A control battery 56 of the usual type is provided for supplying energy to operate the control equipment of the locomotive.

90 Assuming that the apparatus is in the relative position shown in the drawing, also that the engine 17 is operating at the idling speed, the locomotive may be controlled from either side of the cab by means of the auxiliary controllers 35 and 36. It will be assumed that the operator is at the controller 35. By compressing the handle 43, the contact segment 41 is actuated to the "in" position, thereby establishing an energizing circuit for the coil 51 of the relay 47 which causes the armature 48 to be actuated to the closed position. The energizing circuit for the coil 51 may be traced from the positive side of the battery 56, through conductors 57 and 58, contact fingers 59 and 61 bridged by the contact segment 41, conductor 62, operating coil 51 of the relay 47, conductor 63, the resistor 55 and conductor 64, to the negative side of the battery 56.

100 When the armature 48 of the relay 47 is closed, the magnet valve 28 is energized to cause the brakes to be released from the locomotive wheels by means of the brake applicator valve 26, as described hereinbefore. The energizing circuit for the actuating coil of the magnet valve 28 extends from the positive side of the battery 56, through conductors 57 and 65, contact members 66 and 67 of the relay 47, conductors 68 and 69, the actuating coil of the magnet valve 28 and conductors 71 and 72, to the negative side of the battery 56.

115 The master controller 32 may be actuated to position "1" by rotating the auxiliary controller 35 in the proper direction by means of the handle 43. When the master controller 32 is in position "1", the magnet valve 23 is 120 125

energized, thereby opening the throttle 18 to accelerate the engine 17. The energizing circuit for the actuating coil of the magnet valve 23 may be traced from the previously energized conductor 68, through contact fingers 73 and 74 bridged by the contact segment 33 conductor 75, the actuating coil for the magnet valve 23 and conductors 76, 77 and 72, to the negative side of the battery 56. As previously explained, when the coil of the magnet valve 23 is energized, air is admitted to the cylinder 22 to cause the piston 21 to actuate the throttle 18 to the open position, thereby accelerating the engine 17. The motor 10 may be connected to the generator 13 to propel the locomotive by actuating the master controller 32 to position "2" to close the switch 16. The circuit for energizing the actuating coil of the switch 16 extends from the contact finger 78, which engages the previously energized contact segment 33 of the controller 32, through conductor 79, the actuating coil of the switch 16, and conductors 76, 77 and 72, to the negative side of the battery 56. The motor 10 is connected to the generator 15, which is driven by the engine 17, thereby supplying power to operate the motor 10.

A signal lamp 81 is provided to indicate the side from which the locomotive is being controlled and also to warn the operator of a failure of the control voltage. When the contact segment 41 is actuated to the "in" position, a circuit is established for energizing the lamp 81 which extends from the positive side of the battery 56, through the conductors 57 and 58, contact fingers 59 and 82 bridged by the contact segment 41, conductor 83, the lamp 81 and conductors 84 and 64, to the negative side of the battery 56.

In case the handle 43 of the controller 35 is released by the operator, the biasing spring 45 will actuate the contact segment 41 to the "out" position, thereby interrupting the circuit through the contact fingers 59 and 61 to disconnect the coil 51 of the relay 47 from the battery 56.

As previously explained, the armature 48 of the relay 47 will be opened at a predetermined time interval after the coil 51 is de-energized. When the armature 48 is opened, the contact members 66 and 67 are separated, thereby removing control energy from the control apparatus and automatically stopping the locomotive a predetermined time interval after the handle 43 is released.

When the conductor 68 is deenergized by the opening of the contact members of the relay 47, the actuating coil of the switch 16 is deenergized, thereby permitting the switch 16 to open to disconnect the motor 10 from the generator 13. The actuating coil of the magnet valve 23 is also deenergized, which permits the air to be exhausted from the cylinder 22, thereby permitting the throttle 18

to be closed to reduce the speed of the engine 17 to an idling speed. At the same time, the actuating coil of the magnet valve 28 is deenergized, which causes the air brakes to be applied to the wheels of the locomotive, as previously explained. In this manner, the locomotive is automatically stopped in case the operator becomes disabled or leaves the control station for a predetermined time.

If it is desired, the locomotive may be controlled from a different position in the cab by means of the auxiliary controller 36, in the same manner as by the controller 35. The controller 36 is provided with the handle 44 which actuates the contact segment 42. When the handle 44 is depressed, the actuating coil 51 of the relay 47 is energized to close the armature of the relay 47 thereby energizing the control apparatus, as previously explained. The energizing circuit for the coil 51 may be traced from the positive side of the battery 56, through conductors 57 and 85, contact fingers 86 and 87 bridged by the contact segment 42, conductor 88, contact fingers 89 and 61 bridged by the contact segment 41, conductor 62, the actuating coil 51, conductor 63, the resistor 55 and conductor 64, to the negative side of the battery 56.

It will be readily understood that the locomotive will be automatically stopped a predetermined time interval after the handle 44 is released by the operator, in the manner previously described, since the coil 51 of the relay 47 is deenergized when the handle 44 is released.

A lamp 91, similar to the lamp 81, is provided to warn the operator of a failure of the control voltage and also to indicate from which station the locomotive is being controlled.

In order to simplify the drawing and description, only the control equipment pertaining to my invention is illustrated and described. It will be readily understood that additional equipment, of a type well known in the art, such as reversing switches for reversing the motor 10 and also accelerating resistors and switches for controlling the acceleration of the locomotive may be provided.

From the foregoing description, it will be evident that I have provided for controlling the operation of a Diesel-electric locomotive from a plurality of control stations. I have also provided for automatically instituting a braking operation to effect the stopping of the locomotive in the event that the operating handle of a controller is released and permitted to remain in such position for a predetermined interval of time, such as would result were the operator to become disabled or absent himself from his position in the cab for an unpermitted interval of time. The time interval, however, permits

the operator to move from one control station to another without causing the locomotive to be stopped.

I do not desire to be restricted to the specific embodiment of my invention herein shown and described, since it is evident that it may be changed and modified without departing from the spirit and scope of my invention as defined in the appended claims.

10. I claim as my invention:

1. In a control system for motor vehicles, in combination, a motor for propelling a vehicle, a generator for supplying power to the motor, an engine for driving the generator, a controller, disposed to be actuated by an operator, for starting and accelerating the vehicle, and means cooperative with the controller for automatically stopping the vehicle when released by the operator.

20. 2. In a control system for motor vehicles, in combination, a motor for propelling a vehicle, a generator for supplying power to the motor, an engine for driving the generator, electro-pneumatic means for applying brakes to the vehicle, a controller, disposed to be actuated by an operator, for starting and accelerating the vehicle, and means cooperative with the controller for disconnecting the motor and for actuating the brake-applying means to stop the vehicle when the operator becomes disabled.

30. 3. In a control system for motor vehicles, in combination, a motor for propelling a vehicle, a generator for supplying power to the motor, an engine for driving the generator, and means, disposed to be controlled by an operator, for disconnecting the motor from the generator and for reducing the speed of the engine to a predetermined value when released by the operator.

40. 4. In a control system for motor vehicles, in combination, a motor for propelling a vehicle, a generator for supplying power to the motor, an engine for driving the generator, electro-pneumatic means for applying brakes to the vehicle, and means, disposed to be controlled by an operator, for disconnecting the motor from the generator, reducing the speed of the engine to a predetermined value and for actuating the brake-applying means when released by the operator.

50. 5. In a control system for motor vehicles, in combination, a motor for propelling a vehicle, a generator for supplying power to the motor, an engine for driving the generator, a master controller, disposed to be actuated by an operator, for starting and accelerating the vehicle, an auxiliary controller cooperative with the master controller for automatically stopping the vehicle when released by the operator, and means for preventing the stopping of the vehicle for a predetermined time interval after release of the auxiliary controller.

60. 6. In a control system for motor vehicles,

in combination, a motor for propelling a vehicle, a generator for supplying power to the motor, an engine for driving the generator, a master controller, disposed to be actuated by an operator, for starting and accelerating the vehicle, an auxiliary controller cooperative with the master controller for automatically stopping the vehicle when released by the operator, and a relay disposed to delay the stopping of the vehicle for a predetermined time interval after release of the auxiliary controller.

70. 7. In a control system for motor vehicles, in combination, a motor for propelling a vehicle, a generator for supplying power to the motor, an engine for driving the generator, a master controller for starting and accelerating the vehicle, an auxiliary controller adapted to be actuated by an operator and disposed to operate the master controller, means cooperative with the controllers to stop the vehicle when the auxiliary controller is released by the operator, and a relay disposed to delay the stopping of the vehicle for a predetermined time interval after the auxiliary controller is released by the operator.

80. 8. In a control system for motor vehicles, in combination, a motor for propelling a vehicle, a generator for supplying power to the motor, an engine for driving the generator, a master controller for starting and accelerating the vehicle, a plurality of auxiliary controllers adapted to be actuated by an operator and disposed to operate the master controller, means cooperative with the controllers to stop the vehicle when the auxiliary controllers are released by the operator, and a relay disposed to delay the stopping of the vehicle for a predetermined time interval after the auxiliary controllers are released by the operator.

90. 9. In a control system for motor vehicles, in combination, a motor for propelling a vehicle, a generator for supplying power to the motor, an engine for driving the generator, a master controller for starting and accelerating the vehicle, a plurality of auxiliary controllers disposed to actuate the master controller and adapted for manual operation, means cooperative with the controllers to stop the vehicle when the auxiliary controllers are released, a relay disposed to delay the stopping of the vehicle for a predetermined time interval after the auxiliary controllers are released, and signal means for indicating when an auxiliary controller is released.

100. 10. In a control system for motor vehicles, in combination, a motor for propelling a vehicle, a generator for supplying power to the motor, an engine for driving the generator, a switch for connecting the generator to the motor, a master controller for controlling the operation of the switch, an auxiliary controller disposed to actuate the master controller

and adapted for manual operation, means associated with the auxiliary controller for automatically opening said switch to disconnect the motor from the generator when the auxiliary controller is released, and a relay disposed to delay the opening of said switch for a predetermined time interval after the auxiliary controller is released.

11. In a control system for motor vehicles, in combination, a motor for propelling a vehicle, a generator for supplying power to the motor, an engine for driving the generator, a throttle for regulating the speed of the engine, an operating mechanism for actuating the throttle, a master controller for controlling the throttle-operating mechanism, an auxiliary controller disposed to actuate the master controller and adapted for manual operation, means associated with the auxiliary controller for automatically actuating the throttle-operating mechanism to reduce the speed of the engine when the auxiliary controller is released, and a relay disposed to delay the actuation of the throttle-operating mechanism for a predetermined time interval after the auxiliary controller is released.

12. In a control system for motor vehicles having an air-brake system, in combination, a motor for propelling a vehicle, a generator for supplying power to the motor, an engine for driving the generator, a valve for controlling the operation of the air brakes, an electro-pneumatic means for controlling said valve, a controller for controlling said electro-pneumatic means, said controller being adapted for manual operation, means associated with the controller for automatically operating the electro-pneumatic means to actuate the brake-controlling valve when the controller is released, and a relay disposed to delay the actuation of the brake-controlling valve for a predetermined time interval after the controller is released.

In testimony whereof, I have hereunto subscribed my name this 2nd day of March, 1931.

JAMES H. HARVEY.
